UNITED STATES PATENT OFFICE.

JOHN A. MANSON, OF NEW YORK, N. Y.

BRACKET FOR CARD-HOLDERS.

1,035,618.

Specification of Letters Patent. Patented Aug. 13, 1912.

Application filed April 15, 1912. Serial No. 690,958.

To all whom it may concern:

Be it known that I, JOHN A. MANSON, a citizen of the United States, and a resident of the city of New York, borough of Manhattan, in the county and State of New York, have invented a new and Improved Bracket for Card-Holders, of which the following is a full, clear, and exact description.

10 My invention relates to a bracket for pivotally mounting holders for display cards, and an object of my invention is to provide a simple inexpensive holder for card plates so that the latter may be readily 15 and quickly dismounted from the bracket.

Reference is to be had to the accompanying drawings, forming a part of this specification, in which similar characters of reference indicate corresponding parts in all 23 the figures, and in which—

Figure 1 is a front elevation of a preferred embodiment of my invention; Fig. 2 is a longitudinal sectional view through the top of the device shown in Fig. 1, and 25 Fig. 3 is a horizontal transverse sectional view taken on the line 2—2 of Fig. 1; and Fig. 3 is a horizontal transverse sectional view through the top of the device and taken on the line 3—3 of Fig. 1.

I have shown a bracket A more particularly forming the subject-matter of my invention, upon which is pivotally mounted a removable card holder B, upon which is mounted the display or price card C, as is usual with devices of this character. The 33 bracket A is suitably attached to the wall or other support by means of screws D, and has its upper and lower ends outturned to form a perforated upper ledge E and a 35 perforated lower ledge F, alined pairs of perforations G adapted to take pins H projecting from the upper and lower edges of 40 the holder B.

My invention particularly relates to the 45 means for locking the card holder removably in position on the bracket A, and as is usual with devices of this character, the holder B is raised until the lower pin can escape from the lower perforation G. In 50 this instance the upward movement of the pin H is prevented by means of a stop plate 4 extending parallel to the upper ledge E and in its lowered or normal position is disposed a short distance above the pin H, so as not to interfere with the working of the 55 pin, and yet, at the same time, will prevent

the withdrawal of the lower pin from the lower plate F. The plate 4 may be raised into the position shown in dotted lines in Fig. 1, a distance sufficient to permit the withdrawal of the lower pin and the subsequent removal of the holder B. One means for maintaining the plate 4 in either its raised or lowered position is to extend downwardly from the plate and preferably integral therewith, an arm 5, which arm preferably slides through an opening 6 in the plate E and along the upper portion of the front of the bracket A. The arm 5 has extending therethrough a U-shaped slot 7 consisting of an elongated longitudinal portion 8 and upper and lower horizontally-disposed extensions 9, 9 extending in the same direction from the longitudinal portion 8. Extending from the face of the bracket A is a pin 10 projecting through the slot 7.

Bearing upon the side of the arm 5 having the extensions 9, is one end of a flat spring 11, the opposite end of which is suitably fastened to the bracket A, and as shown in the drawings, is threaded through a pair of transversely spaced apertures in the upper ledge E. It will be seen that the tendency of this spring is to maintain the pin 10 in one of the transversely-disposed extensions 9 of the slot 7. In order to raise or lower the plate 4, pressure is brought to bear on the side opposite the spring 11, swinging the plate into the position shown in the inclined dotted lines in Fig. 1, thereby bringing the pin into the elongated portion 8 of the slot 7, permitting the plate 4 to be raised into the dotted position shown at the top of Fig. 1 to permit the insertion or withdrawal of one or all of the plate holders B, after which the plate may be returned to its normal locking position.

Having thus described my invention, I claim as new and desire to secure by Letters Patent:

1. A bracket having upper and lower outturned, perforated ledges, a stop plate disposed above said upper ledge and movable relative thereto, an arm attached to said plate and slidable on said bracket, said arm having a U-shaped slot therein, a pin carried by the bracket and extending through said slot, a spring maintaining said plate with the pin in one of the legs of the U-shaped slot to lock the plate on the bracket, and a holder pivoted in certain perforations

of said ledges and adapted to be prevented from removal therefrom while said stop plate is locked in normal position.

2. A bracket having spaced upper and lower perforated ledges extending therefrom in the same direction, the perforations in said ledges adapted to contain the upper and the lower pivoting pins of a card holder, a locking plate disposed slightly above said upper pin, a pin-and-slot connection between the bracket and the plate permitting the raising of said plate a distance sufficient

to permit the removal of the lower pin from the lower ledge, and a spring cooperating with said locking plate to maintain the same in either its lowered or raised position. 15

In testimony whereof I have signed my name to this specification in the presence of two subscribing witnesses.

JOHN A. MANSON.
